US00D665732S

(12) **United States Design Patent**
Saito et al.

(10) **Patent No.:** US D665,732 S
(45) **Date of Patent:** ** Aug. 21, 2012

(54) **BATTERY**

(75) Inventors: **Masaki Saito**, Tokyo (JP); **Shinji Oda**, Kusatsu (JP)

(73) Assignee: **SANYO Electric Co., Ltd.**, Moriguchi-shi (JP)

(**) Term: **14 Years**

(21) Appl. No.: **29/414,019**

(22) Filed: **Feb. 23, 2012**

(30) **Foreign Application Priority Data**

Sep. 12, 2011 (JP) 2011-020680

(51) **LOC (9) Cl.** **13-02**

(52) **U.S. Cl.** **D13/103**

(58) **Field of Classification Search** D13/102–106, D13/110, 118–119, 184; 429/96–100, 163, 429/176

See application file for complete search history.

(57) **CLAIM**

The ornamental design for a battery, as shown and described.

DESCRIPTION

FIG. 1 is a right rear perspective view of a battery, showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof, the left side elevational view being a mirror image thereof;

FIG. 7 is a cross-sectional view taken along line 7-7 of FIG. 2; and,

FIG. 8 is a cross-sectional view taken along line 8-8 of FIG. 2. The broken lines illustrate environmental structure only and form no part of the claimed design.
